UNITED STATES PATENT OFFICE.

RICHARD J. STREATFEILD, OF BAWTRY, ENGLAND.

COIN-FREED APPARATUS FOR ENABLING SUPPLIES OF WATER OR OTHER LIQUID TO BE OBTAINED.

SPECIFICATION forming part of Letters Patent No. 600,810, dated March 15, 1898.

Application filed September 4, 1897. Serial No. 650,666. (No model.)

To all whom it may concern:

Be it known that I, RICHARD JAMES STREATFEILD, a subject of the Queen of Great Britain and Ireland, residing at Rossington Hall, 5 Bawtry, in the county of York, England, have invented certain Improvements in Coin-Freed Apparatus for Enabling a Supply of Water or other Liquid to be Obtained, of which the following is a specification.

10 The object of my invention is to provide means whereby a predetermined quantity of water or other liquid can be obtained on the insertion of the proper coin or the like into the apparatus, the arrangement being such 15 that only the proper predetermined quantity of water or other liquid can be obtained for the said coin or the like.

According to my invention I provide a cistern or other vessel capable of containing the 20 amount of water or liquid to be drawn off for each payment. At the side of this cistern or vessel is a box or casing inclosing the mechanism which is freed by the coin or the like. This mechanism consists of a device which 25 when in one position engages and locks the inlet-valve for water or liquid to the cistern or vessel and leaves the draw-off valve free to be operated and when in another position engages and locks the draw-off valve and releases the inlet-valve for water or liquid to the 30 cistern or vessel, so that water or liquid cannot flow into the cistern or vessel except when the draw-off valve is closed. The said device is brought into the last-named position 35 by means of a coin or the like inserted into the apparatus and caused to act upon the said device.

I do not limit myself to precise details, but the following is a suitable arrangement of 40 mechanism for the purpose of obtaining a supply of water from a cistern. I will explain it with reference to the accompanying drawings, wherein—

Figure 1 is a side elevation, and Figs. 2 and 45 3 vertical sections, respectively, showing the mechanism in the position in which water is being supplied from the cistern and the position when the coin has acted to release the inlet-valve and lock the draw-off valve. Figs. 50 4 and 5 show details separately.

The cistern A is filled by means of an or-

dinary ball-cock C, to which is attached a disk c, with a slot, recess, or notch c² in it to admit a projection d from the upper arm of a two-armed lever D, centered at d³, which lever is so acted upon by a spring e as to cause the said projection d to engage with the said slot, recess, or notch c² when the ball is raised and the inlet-valve closed, as shown in Fig. 2, so that the ball is prevented from descending even when the water falls, and thus water is prevented from entering the cistern. The other arm of the lever D is formed at d² so as to be capable of engaging with a recess or notch g in a disk G, (shown separately 65 in Fig. 5,) secured to a rod f², passing up into the box or casing B (which incloses the mechanism and protects it from being tampered with) from the plug f of the draw-off valve F and working with it when it is operated by the handle f³. The part d² can only 70 so engage with the notch g, however, when the draw-off valve F is closed, as if the said draw-off valve be not turned off the recess or notch g in the disk G will not be opposite to 75 the tail d² of the lever D, and the latter will be held in position by the edge of the disk G, so that the ball-cock C will not be released. Thus water cannot flow into and out of the cistern A at the same time. To effect the 80 movement of the lever D by a coin, I provide a wheel H, (shown separately in plan and side view in Fig. 4,) in which a slit or recess h is cut across the periphery large enough to hold the coin i, so as to leave a part of it projecting, as shown in Fig. 3. The coin is inserted in a slit b in the box or casing B and conveyed by a flat tube or passage b² into the recess in the said wheel H, the axis of 85 which is carried through the side of the box 90 or casing B and is there provided with a lever-handle h².

Suppose that the cistern A is empty, but the valve C is held in the closed position by the engagement of the projection d of the lever D with the notch c² in the disk c. To obtain a supply of water, the draw-off tap F is turned off, so that the slot g in the disk G in connection therewith comes opposite the tail d² of the lever D. On a coin being passed 95 into the slot b therefor in the box or casing B the said coin will slide down the passage 100

*b*² into the recess *h* in the wheel *H*, so that when the lever-handle *h*² is turned the projecting part of the coin presses against the lever *D*, as shown in Fig. 3, overcoming the force of the spring *e* and releasing the valve *C*. The coin after passing the lever *D* falls into the bottom of the box *B*, and the lever-handle *h*² when released drops back into its original position, where it is held by a stop *h*³, so that the wheel *H* is ready to receive another coin. As soon as the coin ceases to press on the lever *D* the force of the spring is exerted on the lever; but until the cistern *A* is filled with water and the ball floats up the lever *D* is kept in position by the edge of the disk *c* on the ball-valve *C*, thus locking the draw-off valve *F* by reason of the end *d*² of the lever *D* still engaging in the notch *g* in the disk *G*; but when the water has risen to its full height in the cistern *A* the floating up of the ball will bring the notch *c*² in the disk *c* into such a position that the projection *d* of the lever *D* enters the said notch *c*², so as to lock the ball-valve *C*, and the draw-off valve *F* is at the same time released by the end *d*² of the lever *D* leaving the notch *g* in the disk *G*, so that the contents of the cistern *A* can be drawn off.

Instead of the spring *e* a weight can of course be used as the equivalent.

Having now particularly described and ascertained the nature of my said invention and in what manner the same is to be performed, I declare that what I claim is—

1. In a coin-freed apparatus for enabling a supply of liquid to be obtained, the combination of a supply vessel having an inlet-valve and a hand-operated draw-off valve with a locking device adapted to lock the inlet-valve and release the draw-off valve, or vice versa, and means whereby the said lock-

ing device may be operated on the insertion of a coin, substantially as described.

2. In a coin-freed apparatus for the purpose described, the combination with a cistern or vessel, for containing a supply of water or liquid, of a notched disk on the inlet-valve, and a notched disk on the draw-off valve, and a lever whose opposite ends when engaged with the notch in one disk are respectively disengaged from the notch in the other disk, and a coin-receiving wheel and means for operating it to cause the coin to act upon the lever, substantially as hereinbefore described.

3. In a coin-freed apparatus for enabling a supply of liquid to be obtained, the combination of a supply vessel having an inlet-valve carrying a float and a draw-off valve with a locking-lever adapted to lock the inlet-valve and release the draw-off valve, or vice versa, and means whereby the said locking-lever may be operated on the insertion of a coin, substantially as described.

4. In a coin-freed apparatus for enabling a supply of liquid to be obtained, the combination of a supply vessel having an inlet-valve and a hand-operated draw-off valve, with a locking-lever adapted at one end to lock the inlet-valve, and at the other end to release the draw-off valve, or vice versa, and means whereby the said locking-lever may be operated on the insertion of a coin, substantially as described.

In testimony whereof I have signed my name to this specification in the presence of two subscribing witnesses.

R. J. STREATFEILD.
